UNITED STATES PATENT OFFICE.

LEW K. STRANG, OF GLOUCESTER, MASSACHUSETTS.

DESIGN FOR A BREAD-KNEADER.

SPECIFICATION forming part of Design No. 25,167, dated February 11, 1896.

Application filed January 6, 1896. Serial No. 574,548. Term of patent 7 years.

To all whom it may concern:

Be it known that I, LEW K. STRANG, a citizen of the United States, residing in Gloucester, in the county of Essex and State of Massachusetts, have invented and produced a new and original Design for a Bread-Kneader, of which the following is a specification, reference being made to the accompanying drawings, forming a part thereof.

10 Figure 1 shows an underside view of a bread-kneading implement, showing my design; Fig. 2, a plan view of the same, the handle being removed for clearness; Fig. 3, a side elevation and partial section of the implement; and 15 Fig. 4, a detail to be referred to, these four views being deemed necessary to fully illustrate my design.

The leading feature of my design consists in two concentric circular rings, made triangular in cross-section, and radial portions between said rings likewise made triangular in cross-section.

a b represent the two concentric circular rings, each made triangular in cross-section, and *c* represents the intermediate radial portions, likewise made triangular in cross-section. A series of more or less quadrangular openings *d* is thus made to appear in a circle between the two rings *a b*, which are tapering from bottom to top of the rings. The 25 outer ring, *b*, has an annular depression on one side near the edge. The 30

I claim—

The design for a bread-kneading implement, substantially as herein shown and described. 35

In testimony whereof I have signed my name to this specification in the presence of two subscribing witnesses.

LEW K. STRANG.
